UNITED STATES PATENT OFFICE

2,067,113

WORKBENCH

Henry Andreana, New York, N. Y.

Application October 31, 1934, Serial No. 750,880

2 Claims. (Cl. 312—146)

My invention relates generally to workbenches, and particularly to a workbench especially suitable for use by tailors while installing shoulder pads and the like, and an important object of my invention is to provide a workbench of the character described arranged for containing a supply of shoulder pads or other articles being worked upon in a most accessible manner so as to enable the tailor or tailors to have on hand at his bench a greater than usual supply of shoulder pads or the like, and to preserve the shoulder pads before use from dropping on the floor.

Another important object of my invention is to provide a workbench of the character described whereby a large supply of articles being worked upon is maintained in orderly, instantly available condition, so that more work may be done, and the articles prevented from becoming soiled or mussed, and falling on the floor.

Other objects and advantages of my invention will be apparent from a reading of the following description in connection with the drawings, wherein for purposes of illustration I have shown a preferred embodiment of my invention.

In the drawings:

Figure 1 is a top plan view of the embodiment.

Figure 2 is an elevational view of one side thereof.

Figure 3 is a longitudinal sectional view taken through Figure 1 approximately on the line 3—3.

Figure 4 is a transverse vertical sectional view taken through Figure 1 approximately on the line 4—4 looking toward the left in the direction of the arrows.

Figure 5 is an enlarged transverse vertical sectional view taken through Figure 1 approximately on the line 5—5.

Figure 6 is a horizontal sectional view taken through Figure 2 approximately on the line 6—6.

Figure 7 is a transverse vertical sectional view taken through Figure 2 approximately on the line 7—7.

Figure 8 is an enlarged longitudinal sectional view taken through Figure 1 approximately on the line 8—8.

Figure 9 is a perspective view of the false bottom brace and support.

Referring in detail to the drawings, the numeral 5 refers generally to the embodiment which comprises a rectangular metallic container 6 which rests on a centrally located longitudi-

dinal bar 7 which in turn rests on horizontal cross members 8 and 9 which are supported above the floor by and between pairs of legs 10 and 11 which are practically equally spaced from opposite ends of the container 6. Each of the legs has an inwardly bent part 12 intermediate the cross member 8 and to the lower end of the leg which forms a rest for the angularly positioned foot rest 13 which is secured thereto by means of machine screws 14 as shown in Figure 7, the foot rest 13 being located a suitable height above the floor to be comfortable for the workman.

The upper ends of the legs have on the exterior thereof the angle iron framework 15 which is traversed by wood screws 16 which pass upwardly through the flange 17 on the longitudinal sides of the container 6 as shown in Figure 5. The angle irons 15 extend between the legs 10 and 11 on the respective sides of the container 6.

The opposite ends of the container have their upper edges rolled outwardly as indicated at 17' and reinforced with a bar 18 to form a reinforced bead which engages the upper side of a platform 19 at one end of the container and 20 at the opposite end thereof. A frame 21 having an inverted L-shaped cross section rests on top of the side flanges 17 of the container at the longitudinal sides of the container and rests on the platforms 19 and 20 at the ends of the container so as to form a rim around the platforms and at the opposite sides of the container, the frame 21 being secured in place by the screws 16 already alluded to. It will be obvious that the platforms 19 and 20 are supported by the upper cross members 22 and 23 which extend between the pairs of legs.

Resting on the bar 7 and against one end of the container 6 and occupying the space between the last-mentioned end of the container 6 and the legs 11 is a box 24 having a cover 25 hinged as indicated at 26 and provided with a handle 27, the box being provided for containing tools and incidental supplies for the use of the workman.

In the left-hand end of the container 6 is the vertical opening 28, the sides of which have the flanges 29 and 30 acting as guides for the false bottom support generally designated 31.

The member 31 comprises the cylindrical part 32 which is interiorly screw-threaded as indicated at 33 and threaded on the vertical screw 34 which has reduced end portions 35 and 36 journaled in the platform 19 and in the bar 7.

at the left-hand end of the casing 6. The lower end of the screw 34 has a retaining head 37 and on the upper end is an operating handle 38.

The cylindrical element 32 has the lateral flange 39 to which is bolted an L-shaped member 40 which has on its remote end a pair of long legs 41 and 42 arranged in a V configuration which engage and support the underside of the false bottom 43 which is thereby conditioned to be elevated within the container 6 by operation of the screw handle 38. A rivet or bolt 44 passing through the opening 45 in the member 31 and other rivets 46 and 47 passing through holes 48 and 49 in the extremities of the legs 41 and 42 enter the false bottom 43 and connect the false bottom rigidly to the member 31, with the edges of the false bottom closely approaching the sides of the interior of the container 6, with the part 40 of the member 31 extending through the slot 28.

With the construction recited, several days supply of shoulder pads or the like may be placed in the container 6 when the false bottom 43 is in its depressed position and kept in this manner until used. When so contained, the shoulder pads are not subjected to handling and mussing or to falling on the floor to become dirty and unsanitary or to be swept up. As the shoulder pads or the like are used by the tailor, the tailor rotates the handle 38 to bring the top of the shoulder pads or the like to the level of the platforms 19 and 20. By rotating the handle 38 as the shoulder pads or the like are consumed, the tailor is enabled to have at all times a supply of shoulder pads or the like in most accessible position. By reason of the arrangements described a much larger supply of articles may be kept on the workbench than has heretofore been possible or convenient, and the various trips required to replenish the supply of shoulder pads or the like are eliminated, the pads are kept much more accessible, and preserved in better condition for use.

Although I have shown and described herein a preferred embodiment of my invention, it is to be definitely understood that I do not desire to

limit the application of the invention thereto, and any change or changes may be made in the materials, and in the construction and arrangement of the parts, within the spirit of the invention and the scope of the subjoined claims. 5

What is claimed is:

1. A workbench comprising a support frame, an elongated rectangular plate supported by said frame constituting a work surface, an open topped, box-like casing disposed intermediate 10 the length of said plate extending from side to side of the frame, said casing having a vertical slot in one of its side walls, a bar carried by said frame extending from one end to the other centrally below said plate to support said casing, a platform movable in said casing, a support for said platform having an arm extending through the mentioned slot, a screw mounted at its respective ends in said bar and plate, said screw engaging the extending end of said arm, 20 and a hand crank fixed on the upper end of said screw whereby said platform may be manually raised and lowered within said casing.

2. A workbench comprising a rigid support frame, a pair of rectangular plates carried in spaced relation by said frame, a raised rail at the margins of said plates and connecting therebetween, an open topped container disposed in the space between said plates and having beaded edges resting on the adjacent edges of 30 said plates, said container extending downwardly, a support bar carried by said support frame on which said container is seated, said container having an upright slot in one of its end walls and guide flanges at the edges of the 35 slot, a platform movable up and down within said container, a support bracket fixed on the bottom of said platform, an arm extending from said bracket outwardly between the slot flanges, a nut on the extending end of said arm, an upright screw rotatable in said support bar and one of said plates and engaged with said nut, and means on said screw above the plate to 40 manually rotate said screw.

HENRY ANDREANA.

45.
